UNITED STATES PATENT OFFICE.

ALEXANDER F. JENKINS, OF BALTIMORE, MARYLAND.

DESIGN FOR A WELDING TORCH.

60,346.

Specification for Design.

Patented Feb. 7, 1922.

Application filed August 6, 1921. Serial No. 490,421. Term of patent 14 years.

To all whom it may concern:

Be it known that I, ALEXANDER F. JENKINS, a citizen of the United States, residing at Baltimore, Maryland, have invented a new, original, and ornamental Design for Welding Torches, of which the following is a specification, reference being had to the accompanying drawing, forming part thereof, in which—

Figure 1 is a side elevation of the welding torch showing the new design, and

Figure 2 is a section through the same on the line 2—2 of Fig. 1.

I claim as my invention:

The ornamental design for a welding torch as shown in the accompanying drawing.

ALEXANDER F. JENKINS.
